Fort Lauderdale, Fla.

Filed Jan. 25, 1963, Ser. No. 73,309

Term of patent 14 years

(Cl. D45—10)

FIG. 1

FIG. 2

FIG. 3

FIG. 4

FIGURE 1 is a perspective view of a ring embodying my new design;

FIGURE 2 is a front elevational view of the ring of FIGURE 1;

FIGURE 3 is a right-side elevational view of the ring of FIGURE 1; and

FIGURE 4 is a top plan view of the ring of FIGURE 1.

A characteristic feature of the design of my invention resides in the tassels at both ends of the contiguous spiral turns of the ring which tassels are at most of substantially the same thickness as the spiral turns.

I claim:

The ornamental design for a ring, substantially as shown and described.
